ADJUSTABLE SLIDE FOR PUNCH PRESSES

Raymond A. Freeman, Hudson, N. Y., assignor to
 V. & O. Press Company, Inc., Hudson, N. Y., a
 corporation of New York

Application April 22, 1939, Serial No. 269,495

9 Claims. (Cl. 164—106)

This invention relates to punch presses and more particularly to improved means to adjust the slide of punch presses to vary the distance between the bottom of the punch and the top of the die including means to indicate the amount of such adjustment.

In most instances punch presses are equipped with means to adjust the slide relatively to the die supporting bed to vary the distance between the punch and the die but no provision has been made to determine the amount of such adjustment other than by the method of setting the adjustment and then trying it by actual operation of the press on the work. This is both time consuming and wasteful of products, and therefore it is contemplated, as one object of this invention, to improve the slide adjusting means of punch presses by the inclusion in their structure of means to determine, and also to indicate, the amount of such adjustment.

Another object is to provide in a punch press an adjustable slide having means operable thereby, as it is adjusted, to indicate the amount of such adjustment.

Still another object is to provide an improved slide adjusting device having means to measure and indicate the amount the slide is adjusted and which is adapted to indicate when the limit of slide adjustment is reached.

A further object of this invention is to provide in a punch press an improved adjustable slide which will be relatively inexpensive to manufacture, simple in construction, compact, of pleasing appearance, and very efficient and durable in use.

With these and other objects in view, which will appear as the description proceeds, there has been illustrated in the accompanying drawing, one form in which the invention may be conveniently embodied in practice.

In the drawing, wherein like reference numerals designate like parts throughout the several views:

Figure 1 is a front view of a punch press of relatively simple form in the structure of which the features and principles of this invention are embodied;

Figure 2 is an enlarged broken sectional view of the slide and pitman of a punch press, with the improved adjusting means for the slide, taken on line 2—2 of Figure 1;

Figure 3 is an enlarged broken front view of the parts shown in Figure 2; and

Figure 4 is a partially sectioned broken side view of a somewhat modified form of the invention.

Punch presses to which this invention particularly relate generally comprise a frame 11 having a die block holding bed 12 and slide supporting uprights 13 and 14, in which a slide 15 is adapted to be reciprocated. A flywheel 16, usually connected to a source of power either by direct connection or through a belt, is adapted to rotate an eccentric, or crank shaft 17, which acts on a pitman 18 to reciprocate it. The pitman 18 is usually connected to the slide 15 in such a manner that its reciprocating movement is transmitted thereto and that the slide 15 may be adjusted relatively thereto to vary the distance between a punch 19, carried by the slide 15, and a die 21, seated on the bed 12.

The means to adjust the slide, as herein shown, comprises a pitman screw 22 having a threaded shank 23 which is adapted to be screw threaded into a threaded opening 24 provided in the pitman 18 and clamped in position by bolts 25, the pitman 18, in this instance, being split as at 26, for this purpose. A cylindrical portion 27 having wrench rod holes 28 therein, is provided below the threaded shank 23, and a ball-shaped head 29 extends downwardly from the portion 27 to be received and held in a spherical-shaped socket 31 provided in a forwardly protruding portion 32 of the slide 15.

In order to determine and to indicate the amount of adjustment of the slide 15 relatively to the pitman 18 whereby the distance between the punch press 19 and the die is varied, and to measure the amount of such variation in distance between the punch 19 and the die 21, cooperating indicating means is provided between the pitman 18 and a part movable with the slide 15, in this instance, the pitman screw 22. The indicating means for the above purpose is herein shown as comprising a collar 33, which is either formed integral with the pitman screw 22 as an upward extension thereof, or is separate and secured thereto as shown, by shrinking or drive-fitting it thereon, and a bar, or pointer, 34 mounted on, and, as shown, adapted for sliding movement axially of, the pitman 18. In some instances, the bar, or pointer, 34 may be attached to the pitman to be stationary and not slide relatively thereto.

The collar 33 has a series of spaced apart indicating marks 35 provided on its periphery the spacing of which is proportional to the degree of rotation given the pitman screw 22 by a wrench rod inserted in the holes 28. The lower end of the bar, or pointer 34, is arranged to slightly overlap the collar 33 and spaced apart indicating

marks 36 are provided thereon, the spacing of which are such as to permit micrometer readings to be taken by comparing these marks 36 and the marks 35 on the collar 33. The bar, or pointer, 34 is also provided with spaced apart indicating marks 37 along one of its edges, preferably spaced proportional to decimals of an inch, to indicate the amount of relative movement between it and the pitman 18 when compared with a mark 38 provided on the pitman 18 for this purpose.

The bar 34 is provided with a shoulder 39 by which it rests on the collar 33 and due to its weight will follow the collar 33 as the pitman screw 22 is screw-threaded into, or out of, the threaded opening 24 in the pitman 18. The bar 34 is secured to the pitman 18 for sliding movement relatively thereto by being disposed in a slot 40 provided in the face of the pitman 18 for this purpose and by a collar head screw 41 which passes through a lengthwise slot 42 formed in the bar 34. A stop pin 43 is provided in the upper end of the bar 34 and is adapted to engage the collar head 44 of the screw 41 to limit the downward movement of the bar 34. The pin 43 is so disposed that as it engages the head 44 it will cause a separation of the lower end of the bar 34 from the collar 33 and thereby indicate that the limit of adjustment of the pitman screw 22 in the pitman 18 has been reached. A spring 45 may be provided to constantly urge the bar 34 against the collar 33, as indicated in Figure 2, or a positive connection between the collar 33 and the bar may be provided as shown in Figure 4. In the form shown in Figure 4, the bar 50 is provided with a tongue 51 at its lower end which rests in an annular slot 52 provided in the collar 53 whereby a positive action of the bar 50 will be assured.

When it is desired to adjust the distance between the punch 19 and the die 21, the clamp bolts 25 are loosened and the pitman screw 22 is rotated by a wrench rod inserted in the holes 28 therein. The rough amount of such adjustment is observed by comparison of the marks 37 on the side of the bar 34 with the mark 38 on the pitman 18. The finer amount of such adjustment is observed by comparison of the marks 35 on the collar 33 with the marks 36 on the lower end of the bar 34. Due to the relative position of these marks with respect to the pitch of the threads on the threaded shank 23 of the pitman screw 22, actual readings in decimals of an inch are possible and accurate adjustments may be made. After once observing and recording such readings for a given class of work the adjustment may again be made for this class of work in a minimum of time thus resulting in the saving of time and labor.

While there have been shown and described herein two forms in which this invention may be embodied, it is to be understood that the invention is not to be limited thereto but may be embodied in other forms without departing from the spirit and essential attributes thereof. It is therefore desired that the present embodiments be considered in all respects as illustrative and not restrictive, and it will be further understood that each and every novel feature and combination thereof, present in or possessed by, the device herein disclosed, forms a part of the invention included in this application.

What is claimed as new and for which it is desired to secure Letters Patent, is:

1. In a punch press, a reciprocable pitman, a reciprocable slide, means to adjust said slide axi-

ally relatively to said pitman, and means to measure the amount of such adjustment including a member carried by, and movable with, said slide and a member slidably mounted on said pitman and resting on said slide carried member to move it therewith, said slidably mounted member having indicating marks for comparison with a mark on said pitman and marks for comparison with marks on said slide carried member.

2. In a punch press, a reciprocable pitman, a reciprocable slide, an adjustable member to connect said pitman and said slide, and means to measure the amount of adjusting movement of said member including a plurality of marks on said member and a part slidably mounted on said pitman to move with said member as it is adjusted and having a plurality of marks comparative with the marks on said member to determine the amount of such movement, said part having a plurality of marks for comparison with a mark on said pitman.

3. In a punch press, a reciprocable pitman, a reciprocable slide, a member rotatable upon a vertical axis for axially adjustably connecting said pitman and said slide, a plurality of marks on said rotatable member, a part mounted to slide axially with respect to said pitman and engaging to move axially with, said member, marks on said part comparative with the marks on said member to indicate the amount of rotative movement of said member, and said part having other marks comparative with a mark on said pitman to indicate the amount of axial movement of said member.

4. In a punch press, the combination of a reciprocable pitman, a reciprocable slide, a pitman screw adjustably connecting said slide to said pitman, indicating marks disposed peripherally about said pitman screw, a member slidably mounted for axial movement on said pitman and having a mark on its end for comparison with the marks about said pitman screw to indicate the amount of rotation of said screw, said pitman having a mark thereon, and marks on said member for comparison with the mark on said pitman to indicate axial movement of said member and of said pitman screw.

5. In a punch press, a slide, a pitman, means to connect said slide and said pitman and adjust them toward and away from each other, an upwardly facing shoulder on said means, a member slidably mounted on said pitman and resting on said shoulder to move relatively to said pitman when the aforesaid adjustment is made, and co-operating marks on said member and said pitman to indicate the amount of such adjustment.

6. In a punch press, a slide, a pitman, means to connect said slide and said pitman and adjust them toward and away from each other, an upwardly facing shoulder on said means, a member slidably mounted on said pitman and resting on said shoulder to move relatively to said pitman when the aforesaid adjustment is made, cooperating marks on said member and said pitman to indicate the amount of such adjustment, and means to limit the sliding movement of said member relatively to said pitman to separate it from said shoulder and thus indicate the limit of such adjustment.

7. In a punch press, a slide, a pitman, rotatable means to connect said slide and said pitman and adjust them toward and away from each other, an upwardly facing shoulder on said means, a member slidably mounted on said pitman and

resting on said shoulder to move relatively to said pitman when the aforesaid adjustment is made, cooperating marks on said member and said pitman to indicate the amount of such adjustment, 5 and cooperating marks on said means and said member to indicate the amount of rotative movement of said means.

8. In a punch press, a slide, a pitman, rotatable means to connect said slide and said pitman and 10 adjust them toward and away from each other, an upwardly facing shoulder on said means, a member slidably mounted on said pitman and resting on said shoulder to move relatively to said pitman when the aforesaid adjustment is 15 made, cooperating marks on said member and said pitman to indicate the amount of such adjustment, cooperating marks on said means and

said member to indicate the amount of rotative movement of said means, and means to limit the sliding movement of said member to indicate the limit of the adjustment between said slide and said pitman.

9. In a punch press, a reciprocable pitman, a reciprocable slide, a pitman screw rotatably mounted to said slide and screw threaded into said pitman to adjust said slide axially with respect to said pitman when rotated, indicating 10 marks on the periphery of said screw, a pointer on said pitman and adapted to cooperate with said marks to indicate the amount of adjustment between said slide and said pitman and to indicate the limit of such adjustment. 15
